EDWARD S. CORNELL, JR., OF WATERTOWN, CONNECTICUT, ASSIGNOR TO THE CHASE COMPANIES, INCORPORATED, OF WATERBURY, CONNECTICUT, A CORPORATION

TUBE-FLANGING TOOL

Application filed December 26, 1929. Serial No. 416,473.

This invention relates to an improvement in flanging-tools for forming flanges upon the ends of tubes or pipes of malleable metal, such as copper, lead, etc.

The main object of this invention is to provide a simple and convenient tool of the type referred to characterized by its capacity for being readily converted to flange tubes or pipes of various diameters, whereby a flanging outfit may be provided at a low cost for manufacture and with minimum bulk and weight for flanging tubes or pipes of various diameters.

With the above and other objects in view as will appear from the following, my invention consists in a tube-flanging tool having certain details of construction and combinations of parts as will be hereinafter described and particularly recited in the claims.

In the accompanying drawings:

Fig. 1 is an end view of a flanging-tool constructed in accordance with my invention;

Fig. 2 is a view thereof in side elevation;

Fig. 3 is a similar view but with the stop-sleeve in longitudinal section;

Fig. 4 is a view corresponding to Fig. 3 but showing a tube sleeved over the pilot and flanged by engagement with the deflecting-surface;

Fig. 5 is a detached view in side elevation of the mandrel-member; and

Figs. 6, 7, 8 and 9 are corresponding views partly in side elevation and partly in longitudinal section and illustrating a series of

interchangeable stop-sleeves capable of being organized with the mandrel-member to adapt the tool to flange tubes of various diameters.

In carrying out my invention, I employ a mandrel-member 10 consisting of a pilot 11, a conical deflecting-surface 12, an externally-threaded body-portion 13, an annular sleeve-seat flange 14, and a head 15.

The pilot 11 is formed with a tapered outer end 16 and is adapted to be axially entered into a tube 17 (Fig. 4), the end of which it is desired to provide with a flange 18 for the purpose of attaching the tube to a tube-fitting, such as straight-line couplings, T's,

elbows, etc., in accordance with common practice.

In flanging tubes or pipes for the purpose above described, it is necessary to determine and limit the degree to which the tubes are flared and for this purpose I employ a series of stop-sleeves 19^a, 19^b, 19^c and 19^d (four, more or less, in number), each of which is formed with internal threads 20 for inter-engagement with the externally-threaded body-portion 13 of the mandrel 10 and with an inwardly-projecting annular stop-flange 21, the interior surface of which is preferably adapted to snugly fit the deflecting-surface 12 of the mandrel-member when the sleeve in question is applied thereto, and adapted to be engaged by the flange 18 of the tube 17 to limit the outward flare thereof, as clearly shown in Fig. 4.

The stop-sleeves 19^a, 19^b, 19^c and 19^d correspond to each other with the exception that their respective annular stop-shoulders 22 are of different diameters to adapt them to act to limit the flaring of the flanges of tubes of various diameters. For instance, as herein shown, the stop-sleeve 19^a is so proportioned that its annular stop-shoulder 22 is of the correct diameter to determine and limit the flaring action of my improved tool upon a tube of $\frac{3}{8}$ " diameter; similarly, the stop-sleeves 19^b, 19^c and 19^d have their annular stop-shoulders 22 proportioned to limit and determine the flare of $\frac{1}{2}$ ", $\frac{3}{4}$ " and 1" tubes respectively.

In the use of the particular form of my invention herein chosen for illustration, the first step is to apply to the mandrel-member 10 the correct size stop-sleeve for the particular tube which it is intended to flange or flare. This may be readily done by screwing on the desired stop-sleeve, after which the pilot 11 of the mandrel is axially entered into a tube such as 17. Hammer or mallet blows upon the head 15 will serve to drive the deflecting-surface 12 into action to outwardly deflect the end of the tube to form a flange 18.

The driving of the tool into the tube is continued until the edge of the flange 18 thereof firmly abuts against the annular stop-shoulder of the particular stop-sleeve 19^a which at the time is organized with the mandrel-member.

While I have herein shown and described the stop-sleeve 19^a as adapted to be organized with the mandrel by means of screw-threads, it will be apparent without further illustration that my invention comprehends other modes of securing the parts together.

I wish to call attention to the fact that the angle of the deflecting-surface 12 with respect to the axis of the mandrel may vary widely to meet different requirements, and I wish to have it understood, therefore, that my invention is not limited to the inclination of the said deflecting-surface 12 to produce an obtuse-angled flange upon tubes.

It will be seen from the foregoing that by so constructing the mandrel and a series of interchangeable stop-sleeves capable of being organized therewith, I provide a flanging outfit of minimum bulk and weight which may be readily and conveniently converted to accurately flange or flare the ends of tubes of various diameters.

I claim:

1. In a flanging-tool, the combination with a mandrel-member provided at one end with a tube-deflecting surface; of a separately-formed stop-sleeve axially removable from and adapted to embrace a portion of the said mandrel-member and provided with an inwardly-extending annular flange terminating in an annular stop-shoulder located in close proximity to the deflecting-surface of the said mandrel-member to limit and determine the flaring of a tube or similar article thereby, the said annular stop-shoulder constituting the smallest internal diameter of the said sleeve, whereby a flanged tube may be separated from the tool without requiring the demounting of the stop-sleeve from the mandrel-member.

2. In a flanging-tool, the combination with a mandrel-member formed upon its periphery with screw-threads and formed at one end with a tube-deflecting surface; of a separately-formed internally-threaded stop-sleeve adapted to be axially threaded upon the said mandrel-member and provided with an inwardly-extending annular flange terminating in an annular stop-shoulder located in close proximity to the deflecting-surface of the said mandrel-member to limit and determine the flaring of a tube or similar article thereby, the said annular stop-shoulder constituting the smallest internal diameter of the said sleeve, whereby a flanged tube may be separated from the tool without requiring the demounting of the stop-sleeve from the mandrel-member.

3. In a flanging-tool, the combination with

a mandrel-member comprising a relatively-large body-portion, a pilot projecting therefrom for entry into a tube, and a deflecting-surface formed upon the said body-portion and diverging from the base of the said pilot; of a separately-formed stop-sleeve axially removable from and adapted to embrace a portion of the said body-portion and provided with an inwardly-extending annular flange terminating in an annular stop-shoulder located in close proximity to the deflecting-surface of the said body-member to limit and determine the flaring of a tube or similar article thereby, the said annular stop-shoulder constituting the smallest internal diameter of the said sleeve, whereby a flanged tube may be separated from the tool without requiring the demounting of the stop-sleeve from the mandrel-member.

4. In a flanging-tool, the combination with a mandrel-member comprising a relatively-large externally-threaded body-portion, a pilot projecting therefrom for entry into a tube, and a deflecting-surface formed upon the said body-portion and diverging from the base of the said pilot; of a separately-formed internally-threaded stop-sleeve adapted to be axially threaded upon the said externally-threaded body-portion and provided with an inwardly-extending annular flange terminating in an annular stop-shoulder located in close proximity to the deflecting-surface of the said body-member to limit and determine the flaring of a tube or similar article thereby, the said annular stop-shoulder constituting the smallest internal diameter of the said sleeve, whereby a flanged tube may be separated from the tool without requiring the demounting of the stop-sleeve from the mandrel-member.

5. In a flanging-tool, the combination with a mandrel-member comprising a relatively-large body-portion, a pilot projecting therefrom for entry into a tube, a deflecting-surface formed upon the said body-portion and diverging from the base of the said pilot, and a sleeve-seat formed upon the said body-portion at the end thereof opposite the said pilot; of a separately-formed stop-sleeve adapted to embrace a portion of the said body-portion and to bear against the said sleeve-seat and provided with an inwardly-extending annular flange terminating in an annular stop-shoulder engaging the deflecting-surface of the said body-member to limit and determine the flaring of a tube or similar article thereby.

6. In a flanging tool, the combination with a mandrel-member comprising a relatively-large externally-threaded body-portion, a pilot projecting therefrom for entry into a tube, a deflecting-surface formed upon the said body-portion and diverging from the base of the said pilot, and a sleeve-seat formed upon the said body-portion at the end

thereof opposite the said pilot; of a separately-formed internally-threaded stop-sleeve adapted to be threaded upon the said externally-threaded body-portion and to bear against the sleeve-seat thereon and formed with an inwardly-extending annular flange terminating in an annular stop-shoulder engaging the deflecting-surface of the said body-member to limit and determine the flaring of a tube or similar article thereby.

7. In a flanging-tool, the combination with a mandrel-member comprising a relatively-large body-portion, a pilot projecting axially from one end thereof for entry into a tube, of a conical deflecting-surface formed upon the said body-portion and diverging from the base of the said pilot; of a separately-formed stop-sleeve axially removable from and adapted to embrace a portion of the said body-member and provided with an inwardly projecting annular flange terminating in an annular stop-shoulder located in close proximity to the conical deflecting-surface of the said body-member to limit and determine the flaring of a tube or similar article thereby, the said annular stop-shoulder constituting the smallest internal diameter of the said sleeve, whereby a flanged tube may be separated from the tool without requiring the demounting of the stop-sleeve from the mandrel-member.

In testimony whereof, I have signed this specification.

EDWARD S. CORNELL, JR.
